UNITED STATES PATENT OFFICE.

ARTHUR N. ARMSTRONG, OF ONEIDA, NEW YORK.

MANIFOLD HEATER.

Application filed January 27, 1922. Serial No. 532,155.

To all whom it may concern:

Be it known that I, ARTHUR N. ARMSTRONG, of Oneida, in the county of Madison, in the State of New York, have invented new and useful Improvements in Manifold Heaters, 5 of which the following, taken in connection with the accompanying drawings, is a full, clear, and exact description.

This invention relates to a certain new 10 and useful manifold heater.

It is well known that when an internal combustion engine is cold, the vaporization of liquid fuel by the ordinary carburetor is not as complete as is desirable for easy starting of the engine. And for that reason means should be and have been provided located between the carburetor and the cylinder or cylinders, for effecting a more complete vaporization of the liquid fuel. The 20 application of heat to the partially vaporized fuel is a most effective means for producing a further and perhaps practically complete reduction of the liquid to vapor, and the object of this invention is the production of a highly efficient heating element 25 for increasing the degree of vaporization of the fuel on its way from the carburetor to the cylinder.

Other objects and advantages relate to the 30 details of construction, form and arrangement of the heating element, all as will more fully appear from the following description, taken in connection with the accompanying drawings, in which:—

35 Figure 1 is an elevation of a portion of a manifold to which the heating element of my invention has been applied.

Figure 2 is a sectional view of the heating element.

40 As shown, the heating element is inserted in the pipe —2— leading from the carburetor (not shown) to the manifold —3— of an internal combustion engine, the part —2— constituting for all purposes a portion of said manifold. The heating element —1— is preferably constructed in the form shown in Figure 2, and comprises primarily a cup-shaped cap —4— penetrated by a bolt —18—, the head —5— of which constitutes a 45 stop-member preventing endwise removal of the cap —4— in one direction. Within the cap —4— is mounted one end of a resistance element —6— in the form of a cylindrical member, preferably, as shown, having its 50 central portion provided with a plurality of perforations —7—. The interior diameter

of the cylinder —6— is somewhat greater than the external diameter of the bolt or rod —18—, so as to be spaced therefrom throughout its entire length, the spaced positions of said parts being determined and maintained by the cap —4— and the engagement of the cylinder —6— and the bolt —18— therewith. The opposite end of the cylinder —6— is engaged by a tubular connection —8— having its end formed in somewhat conical shape for receiving the end of the cylinder —6—. The lower portion of the external wall of the connection —8— is threaded, as indicated at —9— for engagement with an interiorly threaded tapped opening to be formed in the manifold, or pipe —2—, for rigidly connecting the heating element to the pipe.

55 In addition, the external surface of the connection —8— at the base of the threaded part —9— may be formed with a groove or circumferential recess —20— for the reception of packing or a washer adapted to assist in forming an air-tight connection. The rear portion of the connecting member —8—, as indicated at —10— is formed in the shape of a nut, by means of which the connecting member may be forcibly screwed into the opening tapped in the pipe —2—.

60 Within this connection —8— and surrounding the bolt —18— is a cylindrical insulating block —11— having a base flange —12— projecting outwardly therefrom so as to engage the end of the connection —8— and separate said connection and insulate it from a clamping nut —13— which has a threaded engagement with the threaded end —14— of the bolt —18—, and acts to positively maintain the parts so far named in 65 their desired relative position, as indicated in the drawings.

65 A terminal or binding post —15— is provided, preferably formed with an interiorly threaded recess —16— for threaded engagement with the exposed end of the rod or shaft —18—, and which acts to lock the clamping member —13— in desired position, and maintains the electrical connections in desired contact relation. The electrical circuit may be connected in any suitable manner to the shaft —18— and as shown, is so connected through the medium of the terminal —15—. This electrical circuit may lead from any suitable battery and 70 preferably is provided with a hand switch located within easy reach of the operator of

the vehicle, as for instance, upon the dashboard. The current flows from the battery thru terminal —15—, or directly to the shaft —18—, through the shaft and the cap —4— into the heating element —6—, through the heating element to the connection —8— and through the connection —8— to the manifold or pipe —2— and thereby the current is grounded.

10 Preferably all of the current-carrying parts are of comparatively low resistance, as compared with the cylinder —6—. The essentially novel element of this construction of heating element is the cylinder —6—, which by reason of its form and relation to the other parts of the device is positively and absolutely maintained in its predetermined position without regard to the extent of heating thereof, and which by 20 means of suitable openings —7— can be made to have a high mechanical and electrical resistance at its ends so that the parts that are positively and mechanically gripped by adjacent parts are not weakened, while 25 the electrical resistance of the center portion can be reduced by the formation of suitable perforations. Further, the passage of the vapor through the openings —7— in its movement along the pipe —2— tends, in 30 addition, to break up and disintegrate the partially vaporized liquid. This heating element may be formed of any suitable high resistance material such as carbon or steel, preferably if steel is used, a steel of high 35 carbon content.

It is found in actual practice that it takes but a fraction of a minute to heat the cylindrical element —6— red hot, and that it is maintained in that condition without utilizing a very great amount of current.

It is found sufficient to merely close the switch —17— but a fraction of a minute before it is desired to crank the engine whether manually or by the usual electrical 45 starting means. The cylinder —6— becomes

red hot and increases or practically completes vaporization of the liquid fuel, passing thru the manifold of the engine so that the fuel is supplied to the cylinders in a highly efficient condition, facilitating the 55 easy starting of the engine. The switch may then be closed, and the engine used in the ordinary manner without any further use or loss of current from the battery, so far as this heating element is concerned. It may be 55 desirable to use a switch that is normally opened by springs or otherwise and is maintained in closed position manually for the desired period of time, and then automatically opens by spring-pressure or otherwise 60 in the usual and well known manner.

Altho I have shown and described a specific construction as illustrative of a preferred embodiment of my invention, it will be obvious that various changes in the form, 65 construction and relation of the details of the device may be made without departing from the invention as set forth in the appended claim.

I claim:

A manifold heater comprising a shaft having a head at one end and its opposite end threaded, a cup-shaped cap mounted on the shaft and in contact with said head, a tubular heating element surrounding said 75 shaft and spaced therefrom and having one end fitted within the cap, a tubular connection surrounding the shaft and engaging the other end of said heating element, an insulating block between the shaft and said 80 connection, and a nut engaged with the threaded end of the shaft and in contact with said insulating block for holding said parts in rigid predetermined relation.

In witness whereof I have hereunto set my 85 hand this 19th day of January, 1922.

ARTHUR N. ARMSTRONG.
